William S. Laighton

UNITED STATES PATENT OFFICE.

WILLIAM S. LAIGHTON, OF NORWICH, CONNECTICUT.

PHOTOGRAPHIC HEAD-REST.

SPECIFICATION forming part of Letters Patent No. 237,392, dated February 8, 1881.

Application filed April 28, 1880. (No model.)

To all whom it may concern:

Be it known that I, WILLIAM S. LAIGHTON, of the city of Norwich, county of New London, and State of Connecticut, have invented certain new and useful Improvements in Photographic Head-Rests, which improvements are fully set forth and described in the following specification, reference being had to the accompanying drawing.

10 My improvements are especially adapted to the use of photographers as a support for head-rests in posing a subject to be photographed and to support a camera. It may also be used by surveyors as a support for a transit or level.

15 In the accompanying drawing, A represents a hollow center piece, constructed of any suitable metal, having at its upper end lugs or ears, (shown at a a a.) At its lower end, in line with a a a, are arms b b b, constructed in the 20 form of an arc and radiating from the center piece, A. These arms b b b are provided with lengthwise slots.

25 c c c are made of tubing, and are hinged to the ears a a a. These tubular pieces c c c form the legs to my tripod-stand. In the legs c c c are lengthening-bars B B B, which are secured in their places by thumb-screws d d d.

30 e is an eyebolt, which is slipped over the leg c, and, with its screw end passed through the slot in the arm b, is secured by a thumb-screw, h. The leg c is, by the same movement, drawn against the arm b and held rigidly in position.

In photography it is often necessary to elevate and depress the head-rest as well as the

camera. With my improved stand this is 35 easily accomplished by drawing out or forcing in the lengthening-bars B.

In photographing a male subject or a child it is often impossible to hide the pedestal of a single-stand head-rest so that it will not show 40 in the picture when finished. With my stand this annoying difficulty is overcome by hiding the legs of the head-rest behind those of the subject to be photographed.

It is frequently necessary, in surveying, to 45 place a transit or level close to a fence, house, or other fixed object. This is commonly done by blocking up under one of the legs of the tripod-stand.

By the proper adjustment of the legs c and 50 the lengthening-bars B, an instrument supported by my tripod-stand may be placed as near a fence, house, or other object as may be desired.

I claim—

55 A head-rest constructed with the tubular support A, provided with the pivotal lugs a and slotted radial arms b, in combination with the eyebolts e, nuts h, and legs c, furnished with the extensions B, substantially as described, and for the purpose set forth.

In witness whereof I have hereunto set my hand this 7th day of April, 1880.

WILLIAM S. LAIGHTON.

In presence of—

H. COIT PARK,
WEBSTER PARK.
